UNITED STATES PATENT OFFICE.

FREDERICK SANFORD SEYMOUR, OF MANCHESTER, IOWA.

FUEL FEED FOR HEATING DEVICES.

1,424,041.

Specification of Letters Patent. Patented July 25, 1922.

Application filed October 8, 1921. Serial No. 506,280.

To all whom it may concern:

Be it known that I, FREDERICK SANFORD SEYMOUR, a citizen of the United States, and a resident of Manchester, in the county of 5 Delaware and State of Iowa, have invented a new and Improved Fuel Feed for Heating Devices, of which the following is a full, clear, and exact description.

This invention relates to improvements in 10 fuel feeds for heating devices, an object of the invention being to provide means for gravitationally feeding soft coal impregnated with moisture into the fire pot whereby the combustion of the coal is retarded 15 above the normal level of incandescence, and yet increased heat is produced at the point of incandescence.

In other words, an object of the invention is to provide means for gravitationally feeding 20 soft coal into a fire box in such a manner that a slow burning fire of intense heat will be produced and the consumption of fuel will be comparatively slight.

A further object is to provide a device 25 of this character, which will be simple and practical in construction, strong, durable and efficient in use, and which may be economically manufactured and applied.

With these and other objects in view, the 30 invention consists in certain novel features of construction and combinations and arrangements of parts as will be more fully hereinafter described and pointed out in the claims.

35 In the accompanying drawing:

Figure 1 is a sectional view through a stove showing my fuel feed applied thereto;

Figure 2 is a top plan view of the stove;

Figure 3 is a fragmentary view in trans- 40 verse section on the line 3—3 of Figure 1; and

Figure 4 is an enlarged perspective view of the water container.

Referring in detail to the drawing, 1 in- 45 dicates the fire pot of a stove and 2 the ash space provided with a draft door and damper 3. 4 indicates the grate. 5 indicates the body of the stove extending upwardly from the fire pot and provided at its upper end 50 with an annular bead 6. 7 indicates a cylindrical extension of the stove body, the lower edge portion of such extension fitting around the upper edge of the body 5 and upon the

bead 6. The extension 7 is provided with a laterally extending recessed portion 8 having an orifice 9 around which extends a flange 10 to which is fitted the stove pipe in the usual manner. 12 indicates the stove top provided with a depending flange 13 fitting into the upper end of the stove body 60 extension 7. The top 12 is provided with a central orifice 14. 15 indicates a water container which is in the form of a cylindrical receptacle provided with an outwardly extending annular flange 16 at its upper end. 65 The bottom 17 of the receptacle is provided with a central opening 18 from which extends upward the conical flange 19, the upper edge of which is approximately level with the top of the water receptacle 15. The 70 upper edge of the flange 19 is notched as indicated at 20 for a purpose which will herein-after appear. The receptacle 15 depends through the opening of the stove top and the flange 16 rests upon the stove top around 75 the edge of the opening 14. 21 is the coal feed chute the major portion of which is in the form of an upwardly tapered tube which is contracted at 22 into a reduced portion 23. The reduced portion 23 extends up- 80 ward through the opening 18 of the water receptacle 15 and centrally through the annular flange 19 passing through the open upper end of such flange. 24 is a split collar provided with out-turned portions 25 85 and 26 connected together by a bolt 27. The collar 24 extends around the upper end of the tubular portion 23 and is clamped tight thereon so as to bear upon the upper edge 90 of the flange 19 and form a support from which the chute 21 depends so as to hang centrally within the stove body 5. The lower end of the chute 21 extends into proximity to the fire pot portion 1. 28 is a steam dome, the major portion of which is 95 cylindrical and provided with a closed top 29. 30 is an upward tubular portion extending from the top 29 and provided at its upper end with an opening 31. 32 is a screw cap which is screwed onto the upper end of 100 the tubular extension to form a closure for the orifice 31. 33 is a handle which extends radially from the cap and which forms means for readily unscrewing the cap from the extension 30 when desired. 34 is an 105 annular flange extending from the top 12

and around the opening 14 at the outside of the flange 16 of the water receptacle 15.

In order to supply the chute 21 with coal the dome 28 is lifted out of the water receptacle 15. The water receptacle 15 is also partially filled with water. It will of course be understood that a small fire is first started in the fire pot, access being gained to the fire pot by means of the door and door opening 34 and 35 respectively. The fire is then gradually built up until chute 21 is charged with coal. As the heat of the fire in the fire pot increases, the water in the container 15 is brought to the boiling point and the steam arising therefrom passes up into the steam dome 28 and passes down through the upper tubular end 23 of the chute 21 and percolates down through the mass of coal keeping it moist and into the incandescent portion of the fuel where it is converted into combustible gases which serve to increase the heating qualities of the fire and the moisture at the same time helps to carry down the tarry fluid substances passing from the coal as it is coked.

It will thus readily be seen that the moisture passing down through the mass of coal not only aids to increase the efficiency of the fire but also retards the burning of the fuel supply producing a slow burning fire of great heat and at the same time economizing the consumption of fuel.

When it is desired to draw up the fire quickly I remove the screw cap 32 so as to uncover the orifice 31. The air then passes through such orifice down through the mass of coal and upward towards the chimney opening 9 forming a down draft. As soon as the required heat is attained the screw cap 32 is replaced. I have found it preferable to provide the top of the steam dome 28 with a few perforations 36 to make a slight downward draft to help the steam circulate downward through the coal.

From this description it will be seen that I have devised a fuel feed particularly adaptable for feeding soft clean coal into the fire pot of a stove, furnace or boiler and such as is simple in construction and in which the amount of moisture fed to and through the fuel is automatically controlled by the heat of the fire, that is to say, as the fire increases in heat more steam is generated thereby dampening the coal to a greater degree to retard the fire and as the fire dies down less heat is generated and consequently less steam passes through the coal permitting the fire to burn up to a greater extent. I have provided a flange 34 and notches 20 in order to prevent the water contained in the water receptacle 15 from boiling over and flowing over the top of the stove.

By this means as the water rises above its normal level and over the top of the water

receptacle it passes either through the notches 20 and into the fire or is stopped by the flange 34, the water passing through between the flange 16 and the top of the stove into the fire.

Although I have illustrated one of the preferred embodiments of my invention, it will be apparent that various slight changes and alterations might be made in the general form and arrangement of the parts described without departing from the invention, and hence I do not wish to limit myself to the precise details set forth, but shall consider myself at liberty to make such slight changes and alterations as fairly fall within the spirit and scope of the appended claims.

I claim:

1. In a heating device, the combination with the fire pot, of a fuel feed tube depending towards the centre of the fire pot and having an open upper end, a steam generator into which the open upper end of the feed tube extends, and means for directing the water overflow into the fire pot.

85

2. In a heater, the combination with a fire pot, body and cover having an opening, of a water receptacle depending through the opening, a steam dome fitting into the water receptacle, and a fuel feed tube having an open upper end extending through the body of the receptacle into the steam dome.

95

3. In a heater, the combination with the fire pot, body and cover having an opening, of a water receptacle depending through the opening and provided with an annular flange resting upon the cover around the opening, a steam dome extending into the receptacle, and a fuel feed tube having an open upper end extending through the receptacle into the steam dome.

100

4. In a heater, the combination with the fire pot, body and cover having an opening, of a water receptacle depending through the opening and provided with an annular flange resting upon the cover around the opening, a steam dome extending into the receptacle, a fuel feed tube having an open upper end extending through the receptacle into the steam dome, and an annular barrier extending from the cover and surrounding the flange of the water receptacle.

110

5. In a heater, the combination with the fire pot, body and cover having an opening therein, of a water receptacle depending through the opening having a central orifice in the bottom and an annular flange extending upward from such bottom around the opening, a fuel feed tube having an open upper end extending through the opening formed by the upper end of the annular flange, a projecting portion extending from the feed tube adapted to bear upon the upper end of the flange, and a steam dome extending into the water receptacle.

115

120

125

130

6. In a heater, the combination with the fire pot, body and cover having an opening therein, of a water receptacle depending through the opening having a central orifice in the bottom and an annular flange extending upward from such bottom around the opening and having notches in its upper edge, a fuel feed tube, having an open upper end extending through the opening formed by the upper end of the annular flange, a projecting portion extending from the feed tube adapted to bear upon the up- per end of the flange, and a steam dome ex- tending into the water receptacle.
7. In a heater, the combination with the fire pot, body and cover, of a water recep- tacle depending from the cover, a steam dome extending into the water receptacle having an air inlet at the top, a closure for such inlet, and a fuel feed tube having an open upper end extending through the water receptacle into the steam dome.

FREDERICK SANFORD SEYMOUR.
